HAROLD G. WARR, OF PARK RIDGE, ILLINOIS, ASSIGNOR TO MAINTENANCE EQUIPMENT COMPANY, OF CHICAGO, ILLINOIS, A CORPORATION OF ILLINOIS

OPERATING MECHANISM FOR RAIL OILERS

Application filed January 20, 1930. Serial No. 422,125.

This invention relates to certain new and useful improvements in operating mechanism for rail oilers, and more particularly to a mechanism for utilizing the wave motion of a rail as a train passes thereover, as a source of power for operating the oil propelling mechanism.

At certain locations in a railway track, particularly along curves, it is desirable to distribute oil along the inner surface of the rail head and the engaging inner surfaces of the car wheel flanges to minimize the wear caused by these engaging parts. Such oiling devices usually comprise a reservoir containing the oil supply, and means for forcing oil from this reservoir and distributing it along the rail head or projecting it against the car wheel flange. The oil-lifting or pumping mechanism is usually operated by a treadle or plunger that is depressed by some portion of each car wheel as it passes along the rail. Such mechanisms are open to the objection that the contact with the wheel is too sudden and violent, and that there are many more impulses than are necessary due to the great number of supporting wheels for the cars or other vehicles.

According to this invention an entirely different principle is utilized for driving the oiling mechanism, the power for propelling the oil being derived from the wave motion in the rail itself as the load supported thereby passes along from one portion of the rail to another. It is well known, that despite the strength and rigidity of the steel rail, the rail weaves up and down to an appreciable extent as the great weight of the car is transferred from one portion of a rail to another. As is well known, each modern railway car is of considerable length, and its weight is sustained by the truck or group of wheels at each end thereof. A considerable length of rail between these trucks does not directly sustain this weight, and consequently the rail will be depressed under each truck and will rebound or bow upwardly between these points when relieved of the weight of the car. Since the trucks or groups of wheels at the adjacent ends of two coupled cars are positioned quite close to one another compared

with the distance between the trucks at either end of each car, the rail may be considered as having one depressed portion positioned under the trucks at the ends of two coupled cars and one upwardly bowed portion intermediate the ends of each car. In other words, there will be one complete wave in the track for each car that passes along the track. The lengths or magnitudes of these waves may vary in accordance with the length of car, or the weight thereof, but these variations are immaterial as far as the present invention is concerned. This depression of the track between the crest and the trough of the wave varies in accordance with the factors noted hereinabove and the character of the roadbed, and will vary in magnitude from a small fraction of an inch to an inch or more.

According to the present invention, two operating members are anchored to the track at positions spaced apart longitudinally of the rail far enough to occupy materially different positions in the wave of the track, and the relative vertical movements between these members is utilized to transmit power for operating the oiling mechanism, or other apparatus. In the specific embodiment of the invention here disclosed, a rotary shaft carrying a ratchet wheel is journaled in a bracket secured to one portion of the rail. A rigid bar extending longitudinally of the rail is anchored to the rail at points sufficiently remote from the bracket to be positioned in a different portion of the rail-wave. The free end of the bar carries a pawl which yieldably engages the ratchet wheel so that as the bar moves up and down due to the wave motion of the rail, the ratchet wheel and the shaft on which it is positioned will be intermittently rotated in one direction.

The principal object of this invention is to provide a new and improved operating mechanism for rail oilers or other purposes, as briefly described hereinabove and disclosed more in detail in the specifications which follow.

Another object is to provide an improved track oiling assembly driven from the wave motion of the track rail.

Other objects and advantages of this in-

vention will be more apparent from the following detailed description of certain approved forms of apparatus adapted for carrying out the principles of this invention.

5 In the accompanying drawings:

Fig. 1 is a plan view of a track oiler assembly embodying the improved operating mechanism.

10 Fig. 2 is a transverse vertical section, taken substantially on the line 2—2 of Fig. 1.

Fig. 3 is a longitudinal vertical section, taken substantially on the line 3—3 of Fig. 2.

15 Figs. 4, 5, 6 and 7 are diagrammatic views illustrating successive positions of the operating mechanism.

Fig. 8 is a partial plan view, partly in vertical section, showing a modified form of the invention.

20 Fig. 9 is a perspective view showing a modified means for anchoring the operating parts to the rail.

Fig. 10 is a partial perspective view showing an alternative method of adjusting the length of the operating bar.

25 The rail 1 is supported in the usual manner on the ties 2 imbedded in the roadbed 3. Track oiling mechanisms of many different forms may be used, the specific form here shown by way of example being more fully disclosed in the copending application of Bates and Overmier, Serial No. 397,413, filed October 4, 1929. A casing 4 imbedded in the roadbed 3 at the outside of the trackway houses a reservoir for the oil supply and a rotary pumping mechanism for forcing oil from the reservoir through conduit 5 which extends under the track to a distributing bar 6 supported along the inner side of the rail and provided with a plurality of spaced outlets 7 through which the oil is ejected to be engaged by the passing car wheel flanges and spread along the rail side and the surfaces of the wheel flanges.

30 A bracket 8 is anchored in any suitable manner to the opposite or outer side of the rail. In the example here shown, bolts 9 pass through the web 10 of the rail and filler plates 11 to hold in place the bracket 8 and also the distributing mechanism 6. The bracket 8 is formed with a pair of coaxial bearings 12 and 13, the rotary shaft 14 being journaled at its inner end in the bearing 12, and a sleeve member 15 slidably keyed at 16 to the shaft 14 being journaled in the bearing 13. A ratchet wheel 17 is rotatably mounted on shaft 14 between the bearings, and a pair of similar friction discs 18 are interposed between the respective sides of the ratchet wheel and a thrust plate 19 keyed to shaft 14 and a thrust plate 20 at the inner end of sleeve 15. A coiled spring 21 is compressed between the outer end of sleeve 15 and an adjusting nut 22 on shaft 14. The spring 21 serves to thrust the sleeve 15 inwardly so as to firmly clamp the ratchet wheel 17 between the friction discs

18 whereby it will normally rotate with the shaft 14. This friction clutch arrangement is merely to permit the ratchet wheel to rotate on the shaft in case parts of the mechanism becomes locked, rather than cause breakage of any of the parts.

70 In normal operation the ratchet wheel 17 and shaft 14 rotate as a unit, and the other features of this invention would be entirely operative if wheel 17 were keyed directly to shaft 14. Shaft 14 is connected through the universal joints 23 and the telescopic shaft 24 with the rotary driving shaft 25 for the pumping mechanism within casing 4. It will be apparent that this flexible shaft connection will permit relative movements or displacements of the rail and reservoir casing without affecting the operation of the assembly.

75 The improvements which constitute the particular subject matter of this invention relate to a means for imparting rotative movement to the ratchet wheel 17 and driving shaft 14 automatically as a train passes along the tracks. A rather long rigid bar 26 is anchored adjacent one of its ends and at a point intermediate its length to the side of web 10 of rail 1 at positions remote from the ratchet wheel 17. As indicated in Fig. 3, the bar 26 is anchored to a pair of brackets 27 by bolts 28, the brackets 27 being fitted between the head 29 and base flange 30 of the rail and held in place by passing the bolts 28 through the web 10 of the rail. As an alternative method of anchoring the bracket 27 to the rail, clamping devices 31 (see Fig. 9) in the nature of rail anchors could be used to clamp the lower portions of the bracket to the base flange 30. It will be apparent that this latter method of anchoring the bracket members to the rail could also be used to fasten in place the bracket 8, and the guide bracket 32 hereinafter referred to. The two anchorage points 28 for bar 26 may be closely adjacent one another and adjacent one end of the bar, as shown in Fig. 9, or one of the anchorage points may be adjacent the end of the bar and the other at a point substantially midway the length of the bar, as in Figs. 3 to 7 inclusive. If the two anchorage points are any material distance apart the bar will pivot about the bolts 28 as the rail flexes so that the bar 26 between the points 28 will form a chord of the arc of the rail between these points.

100 The bar 26 may be provided with a plurality of spaced holes 33 for receiving the bolts 28 whereby the effective length of bar 26 may be adjusted. In the modification shown in Fig. 10, the bar 26 is composed of two sections 34 and 35 connected by bolts 36 passing through selected openings 37 whereby the effective length of the bar may be adjusted.

105 A pawl device 38 provided with a plurality of teeth 39 adapted to engage the teeth 110

40 of ratchet 17, has a shank or stem 41 slidably fitted within a passage 42 in the free end of bar 26, and a compression spring 43 confined in passage 42 behind the stem 41 5 tends to force the pawl device yieldably into engagement with the ratchet wheel. A stop pin 44 passing through an elongated slot 45 in stem 41 serves to limit the longitudinal movement of the pawl device. It will now 10 be apparent that as the pawl device 38 is elevated with respect to ratchet wheel 17, the spring 43 will yield and permit the pawl teeth 39 to slide up over the ratchet teeth 40. When the pawl device 38 is depressed, the 15 pawl teeth 39 will engage certain of the teeth 40 and impart a partial rotation (in a counter clockwise direction, Fig. 3) to the ratchet wheel 17 and the shaft 14 on which it is mounted. If it were desired to rotate the 20 shaft 14 in the opposite, or clockwise direction, it is merely necessary to reverse the direction of the teeth 39 and 40, and this can easily be accomplished by simply reversing the positioning of the pawl device 38 and 25 ratchet 17 in the bar 26 and on the shaft 14 respectively. A locking pawl 46 pivoted at 47 to a portion 48 of the bracket 8 engages the teeth 40 of ratchet 17 and prevents retrograde rotation of the ratchet wheel during 30 the idle stroke of the pawl device 38. A guide bracket 32 is anchored to the rail in any suitable manner as indicated at 49 and is provided with a vertical slot 50 through which bar 26 passes so that the bar is held 35 against lateral movement with respect to the rail but is permitted free vertical movement with respect thereto.

The operation of this portion of the mechanism will be better understood by reference 40 to the diagrammatic views shown in Figs. 4 to 7 inclusive. In these views 51 indicates one of the car trucks, or a pair of adjacent car trucks, and in a similar manner 52 indicates the truck at the opposite end of a car. 45 The trucks 51 and 52 are assumed to be traveling from left to right as seen in these figures. Directly beneath the load or truck 51 there will be a trough 53 of a wave in the track 1, and in front and in the rear of this 50 trough will be two wave crests 54. The same is true of the truck or load 52, and of all of the following trucks. The magnitude of these track waves is greatly exaggerated in these figures in order to facilitate the disclosure. In Fig. 4, the train has not yet reached 55 that portion of rail 1 to which the bar 26 and ratchet 17 are anchored, and these members remain in normal alignment, similar to that indicated in Fig. 3. When truck 51 reaches 60 the position shown in Fig. 5, bar 26 and ratchet 17 will be located on one of the upwardly flexed portions of a wave. Since the rigid bar 26 is only anchored to the rail at one end and at an intermediate point, it is 65 not compelled to join in the flexing movement of the rail, but its free end will be tilted upwardly with respect to the rail so as to elevate the pawl device 38 with respect to ratchet wheel 17. As truck 51 advances to the position shown in Fig. 6, the bar 26 and ratchet 17 will now be located on one of the downwardly flexed portions of rail 1, and during this movement the free end of bar 26 carrying the pawl 38 is swung downwardly, this being the operative stroke which imparts a partial rotation to the ratchet wheel 17. As truck 51 advances to the position shown in Fig. 7, the pawl will again be swung upwardly, this being the idle stroke of the pawl device. As 70 the following truck 52 advances along the rail this cycle of movements will be repeated. It will now be apparent that there will be one complete track wave for each car in the train and that the pawl device 38 will be given one operative stroke for each wave. 75

It will be noted that even though the train is proceeding along the trackway at high speed, there will be no sudden movements or violent impacts imparted to any portion of this operating mechanism. Furthermore, 80 there will be only one rotative impulse imparted to shaft 14 for each car of the train, and this rotation will be comparatively small, whereas in those prior forms of operating mechanism actuated by the car wheels there 85 will be one impulse for each wheel passing along the rail and the violence of the sudden contact with the wheel is apt to cause a greater rotative movement than is desirable. It is only necessary and desirable that the oil 90 be very slowly forced through the distributing openings 7 in the distributing bar 6, so that it in effect slowly oozes out of these openings into position to be wiped away by the passing car wheel flanges. The sudden ejection of oil through these outlet openings is to 95 be avoided if possible, since this is wasteful and furnishes an excessive amount of oil. This present improved operating mechanism 100 produces the desired slow movement of the 105 pumping mechanism.

In the modification shown in Fig. 8, the oil pumping and distributing device 55 is of a type located adjacent the side of the rail 1, with the operating driving shaft extending 110 parallel with the rail. The driving shaft 56 is journaled in the bracket 57 (secured to the side of the rail in place of the bracket 8 heretofore described,) and the ratchet wheel 58 is mounted on shaft 56. It may be frictionally secured to this shaft in the same manner as previously described. The pawl device 59, which may be essentially of the same construction as the pawl 38 previously described, 115 is mounted in the side of the end portion of operating bar 26 instead of in the end thereof. The general operation of this mechanism differs in no essential respect from the first described form of the invention.

While this improved operating mechanism 120

is designed especially to operate a track oiler of the types hereinabove described and forms a new and efficient combination therewith, it will be apparent that this operating mechanism might be utilized to drive other forms of apparatus associated with a trackway, and it is contemplated that such uses should fall within the scope of this invention.

I claim:

- 1. Mechanism for utilizing power derived from the wave motion of a railway rail caused by the passage of a load along the rail, comprising cooperating members supported by the rail and movable relative to one another as the rail flexes.
- 2. Mechanism for utilizing power derived from the wave motion of a railway rail caused by the passage of a load along the rail, comprising a pair of members anchored to the rail at positions spaced longitudinally of the rail, said members projecting into proximity to one another, and engaging means carried by the two members and actuated by the relative movement of the members.
- 3. Mechanism for utilizing power derived from the wave motion of a railway rail caused by the passage of a load along the rail, comprising a pair of members anchored to the rail at positions spaced longitudinally of the rail, said members projecting into proximity to one another, and a pawl and ratchet mechanism carried by the two members whereby the ratchet will be rotated as the members move relative to one another.
- 4. Mechanism for utilizing power derived from the wave motion of a railway rail caused by the passage of a load along the rail, comprising a substantially rigid bar extending longitudinally of the rail and having one end portion anchored to the rail, the other end portion being free to move vertically with respect to the adjacent portion of the rail, and a movable member supported on the rail adjacent the free end of the bar and adapted to be actuated thereby.
- 5. Mechanism for utilizing power derived from the wave motion of a railway rail caused by the passage of a load along the rail, comprising a substantially rigid bar extending longitudinally of the rail and having one end portion anchored to the rail, the other end portion being free to move vertically with respect to the adjacent portion of the rail, and a rotary member supported on the rail adjacent the free end of the bar and adapted to be actuated thereby.
- 6. Mechanism for utilizing power derived from the wave motion of a railway rail caused by the passage of a load along the rail, comprising a substantially rigid bar extending longitudinally of the rail and having one end portion anchored to the rail, the other end portion being free to move vertically with respect to the adjacent portion of the rail, a rotary shaft supported on the

rail adjacent the free end of the bar, and interengaging means on the shaft and bar adapted to rotate the shaft as the bar moves vertically.

7. Mechanism for utilizing power derived from the wave motion of a railway rail caused by the passage of a load along the rail, comprising a substantially rigid bar extending longitudinally of the rail and having one end portion anchored to the rail, the other end portion being free to move vertically with respect to the adjacent portion of the rail, a rotary shaft supported on the rail adjacent the free end of the bar, a ratchet wheel secured on said shaft, a pawl movably supported at the end of the bar, and a spring for yieldingly urging the pawl into engagement with the ratchet.

8. Mechanism for utilizing power derived from the wave motion of a railway rail caused by the passage of a load along the rail, comprising a bracket anchored to the rail, a rotary shaft journaled in the bracket, a ratchet wheel on the shaft, a substantially rigid bar extending longitudinally of the rail and having one end portion secured to the rail at spaced positions remote from the bracket, and a pawl carried by the free end of the bar and engaging the ratchet wheel.

9. Mechanism for utilizing power derived from the wave motion of a railway rail caused by the passage of a load along the rail, comprising a bracket anchored to the rail, a rotary shaft journaled in the bracket, a ratchet wheel on the shaft, a substantially rigid bar extending longitudinally of the rail and having one end portion secured to the rail at spaced positions remote from the bracket, a pawl mechanism slidably mounted in the free end portion of the bar, and means for yieldingly urging the pawl mechanism into engagement with the ratchet wheel.

10. The combination with apparatus for oiling a railway rail comprising a reservoir, and means for forcing oil from the reservoir and for distributing this oil at the side of the rail head, of mechanism for driving the oiling apparatus comprising cooperating devices anchored to the rail at positions spaced longitudinally thereof and actuated by the wave motion of the rail as a load passes therealong.

11. The combination with apparatus for oiling a railway rail comprising a reservoir, and means for forcing oil from the reservoir and for distributing this oil at the side of the rail head, of mechanism supported by the rail for giving one impulse to the oiling apparatus for each car of a train that passes along the track.

12. The combination with apparatus for oiling a railway rail comprising a reservoir, and means for forcing oil from the reservoir and for distributing this oil at the side of the rail head, of mechanism for driving the oiling

apparatus comprising cooperating devices supported entirely by the rail and actuated by the wave motion of the rail as a load passes therewith.

13. The combination with apparatus for oiling a railway rail comprising a reservoir, and means for forcing oil from the reservoir and for distributing this oil at the side of the rail head, of mechanism for driving the oiling apparatus comprising a bracket fixed to the rail, a rotary shaft journaled in the bracket, and mechanism comprising a bar extending parallel to the rail and anchored to the rail at points remote from the bracket for imparting rotary movements to the shaft as the rail flexes from its normal parallelism with the bar.

14. The combination with apparatus for oiling a railway rail comprising a reservoir, and means for forcing oil from the reservoir and for distributing this oil at the side of the rail head, of mechanism for driving the oiling apparatus comprising a bracket fixed to the rail, a rotary shaft journaled in the bracket, a ratchet wheel on the shaft, a bar extending parallel to the rail and anchored to the rail, at positions remote from the bracket, and a pawl device carried by the bar and engaging the ratchet wheel.

15. The combination with apparatus for oiling a railway rail comprising a reservoir, and means for forcing oil from the reservoir and for distributing this oil at the side of the rail head, of mechanism for driving the oiling apparatus comprising a bracket fixed to the rail, a rotary shaft journaled in the bracket, a ratchet wheel on the shaft, a bar extending parallel to the rail and secured to the rail at positions remote from the bracket, and a pawl device slidably mounted in the free end of the bar, and means for yieldingly urging the pawl device into engagement with the ratchet wheel.

16. The combination with apparatus for oiling a railway rail comprising a reservoir and means for forcing oil from the reservoir and for distributing this oil at the side of the rail head, of mechanism for driving the oiling apparatus comprising a bracket fixed to the rail, a rotary shaft journaled in the bracket, a ratchet wheel on the shaft, a bar extending parallel to the rail and pivotally secured to the rail at an intermediate point and adjacent the end remote from the ratchet wheel, and a pawl carried by the free end of the bar and engaging the ratchet wheel.

17. The combination with apparatus for oiling a railway rail comprising a reservoir and means for forcing oil from the reservoir and for distributing this oil at the side of the rail head, of mechanism for driving the oiling apparatus comprising a bracket fixed to the rail, a rotary shaft journaled in the bracket, a ratchet wheel on the shaft, a bar extending parallel to the rail and pivotally se-

cured to the rail at an intermediate point and adjacent the end remote from the ratchet wheel, and a pawl device slidably carried by the free end of the bar and means for yieldingly urging the pawl device into engagement with the ratchet wheel.

18. Mechanism for utilizing power derived from the wave motion of a railway rail caused by the passage of a load along the rail, comprising a substantially rigid bar extending longitudinally of the rail and pivotally secured to the rail at an intermediate point and adjacent one end of the bar, the other end portion being free to move vertically with respect to the adjacent portion of the rail, and a means supported on the rail adjacent the free end of the bar and adapted to be actuated by the vertical movement thereof.

19. Mechanism for utilizing power derived from the wave motion of a railway rail caused by the passage of a load along the rail, comprising a substantially rigid bar extending longitudinally of the rail and pivotally secured to the rail at an intermediate point and adjacent one end of the bar, the other end portion being free to move vertically with respect to the adjacent portion of the rail, a rotary shaft supported by the rail adjacent the free end of the bar, and interengaging means on the shaft and bar adapted to rotate the shaft as the bar moves vertically.

20. Mechanism for utilizing power derived from the wave motion of a railway rail caused by the passage of a load along the rail, comprising a substantially rigid bar extending longitudinally of the rail and pivotally secured to the rail at an intermediate point and adjacent one end of the bar, the other end portion being free to move vertically with respect to the adjacent portion of the rail, a rotary shaft supported by the rail adjacent the free end of the bar, a ratchet wheel secured on the shaft, a pawl movably supported at the free end of the bar, and a spring for yieldingly urging the pawl into engagement with the ratchet wheel.
